GRAND PIANO

William Millington, Grand Rapids, Mich., and Wilbur M. Day, Kenwood, Ohio, assignors to The Baldwin Piano Company, Cincinnati, Ohio, a corporation of Ohio

Application January 27, 1958, Serial No. 49,406

Term of patent 14 years

(Cl. D56—9)

Fig. 1 is a perspective view of a grand piano, showing our new design;

Fig. 2 is a sectional view taken on the line 2—2 of Fig. 1;

Fig. 3 is a sectional view taken on the line 3—3 of Fig. 1;

Fig. 4 is a top plan view of the leg; and

Fig. 5 is a partial front elevational view of the leg.

The three legs are identical in shape and form.

The dominant features of our design reside in the portions shown in full lines.

We claim:

The ornamental design for a grand piano, substantially as shown and described.
